Primary Examiner — S. Bryan Reinholdt, Jr.*Assistant Examiner* — James T Tyree(74) *Attorney, Agent, or Firm* — Hawaii Patent Services; Nathaniel K. Fedde; Kenton N. Fedde(57) **CLAIM**

The ornamental design for an electric vehicle toy, as shown and described.

DESCRIPTION

FIG. 1 is a front, left, top perspective view of an electric vehicle toy, showing my new design;

FIG. 2 is a rear, right, top perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a partial enlarged view of FIG. 1; and,

FIG. 9 is a partial enlarged view of FIG. 5.

The evenly spaced broken lines shown in the drawings depict portions of the electric vehicle toy that form no part of the claimed design.

The dash-dot-dash broken lines are for notating enlarged views and form no part of the claimed design.
